CLAIM

The ornamental design for an industrial container dolly, as shown and described.

DESCRIPTION

FIG. 1 is a top perspective view of a industrial container dolly showing our new design, the broken lines are for illustrative purposes and form no part of the claimed design;

FIG. 2 is a top plan view thereof;

FIG. 3 is a side elevational view thereof; and,

FIG. 4 is a bottom view.

FIG. 1

FIG. 3
